VAPOR PHASE METHOD OF OIL CONVERSION

Application filed February 21, 1928. Serial No. 256,038.

This invention relates to improvements in the manufacture of motor fuels, and has particular reference to an improved vapor phase method of producing low boiling hydrocarbon compounds from relatively higher boiling point compounds.

In accordance with the present invention a method of cracking is provided consisting in passing a current of oil vapor through a 10 tubular converting element, within which element there is positioned a core of a catalytic or contact material, and wherein provision is made for heating the current of oil vapor during its travel through the converting element and around said core so that when such oil vapor is discharged from the converting element it attains a temperature in excess of 1000° Fah.

In the operation of a vapor phase system 20 of this kind it has been the practice heretofore to pass the oil vapors through the converting element or elements at a progressively increasing velocity from the inlet to the outlet terminal portions of such elements.

I have observed in the operation of such 25 systems that where the oil vapors are initially introduced into the converter element, or where the oil vapors are at lowest temperature, that is temperatures below 1000° Fah., coke or carbon accumulates rapidly on the walls of the converting element or catalyst core. This coke or carbon tends to obstruct the free passage of the oil vapors 30 through the converting element and also interferes with the proper transfer of heat 35 from the walls of said element to the oil vapor. In certain instances, however, it has been observed that when there is a small amount of carbon deposit on the walls of the

40 converter a beneficial action is secured in the matter of gasoline recovery and in minimizing the formation of non-combustibles. I attribute this to the fact that the accumulated carbon decreases the effective area of the converter with the result that the velocity of 45 travel of oil vapor is increased at the point of oil vapor introduction into the converter. The increased velocity results in more rapid heat transference so that a shorter time ensues in raising the temperature of the oil 50

vapor to a critical temperature in excess of 1000° Fah.

It is, therefore, one of the outstanding objects of the present invention to provide a vapor phase system of oil conversion wherein 55 the velocity of travel of the oil vapors in the inlet portions of the converter is materially greater than that which obtains in the discharge portions of the converter. This result is secured by controlling the effective 60 area of the inlet portion of the converter with respect to the corresponding area of the outlet portion of said converter. By this manner of operation I am enabled to provide oil vapor velocities of between four to seven 65 thousand feet per minute in the inlet portion of the converter and from two to four thousand feet per minute in the outlet portion of the converter. As stated, by restricting the effective area of the inlet portion of the converter, greater velocity is obtained in this 70 portion of the apparatus, by means of which improved heat transference is procured and the interval of time necessary to raise the oil vapor to a temperature above 1000° Fah. 75 is materially reduced as compared with constructions providing for uniform flow of the oil vapor. By minimizing the time element in raising the oil vapor to a critical temperature I also minimize the release of free carbon or coke from the oil vapor and the resultant deposition of this carbon or coke on the 80 walls of the converter and catalyst core.

Among several preferred methods of 85 procuring these ends, I have found it to be most satisfactory to employ a converter consisting of uniform standard tubes of uniform cross sectional area throughout, and to position within such a tube, and in axial relation therewith, a core of a catalytic material such as 90 molded concrete containing ferrous oxide. This core is of substantially cylindrical form and is so mounted within the tubular converting element that there is produced between the walls of said core and the complementary 95 inner walls of the tube, an annular space through which the oil vapor sweeps. I have found that by tapering the core slightly from the inlet end of the converter element to the outlet end thereof, a very effective method is

provided for regulating the area of oil vapor flow through the converter element. By this simple expedient I am enabled to obtain any desired velocity of oil vapor flow through 5 any part or parts of the converter element.

For an understanding of the invention reference is to be had to the accompanying drawing wherein:

Figure 1 is a vertical sectional view taken 10 through an oil heater or converter formed in accordance with the present invention.

Figure 2 is an enlarged vertical sectional view taken through one of the tubes or elements of the converter provided with a catalytic core. 15

Figure 3 is a transverse sectional view on the plane indicated by the line $x-x$ of Figure 2.

Figure 4 is a similar view taken on the 20 line $y-y$ of Figure 2 through a portion of the core having a smaller diameter.

Referring more particularly to the accompanying drawing, the numeral 1 designates an oil heater or converter of the type employed in connection with vapor phase methods of oil decomposition. The heater is formed to include the customary setting 2 in which is positioned a vertically and transversely disposed bridge wall 3, the latter serving to divide the interior of the setting 25 into burner and tube compartments 4 and 5 respectively.

Supported by the walls of the setting 2 and also the bridge 3 are a plurality of converting tubes 6, the latter being arranged in rows, with the upper row of tubes, indicated at B, arranged to pass through the front and rear walls of the setting and also the spaced double walls of the bridge 3. The upper row of 30 tubes is connected at its discharge end by means of return bends or header 7 with the next lower row of tubes, and this row of tubes, as well as the remaining rows, are supported by the bridge wall 3 and the rear wall of the 35 setting 2. Oil vapor is adapted to enter the forward end of the upper row B of tubes 6, in order that the oil vapors may be subjected to the developed heat within the setting and conversion temperatures in excess of 1000° 40 Fah. secured. If desired, steam may be added to the oil vapors prior to the introduction of 50 such vapors into the inlet end of the converter.

Arranged within each of the tubes 6, and 55 extending longitudinally and axially, is a core 8 which is preferably formed from molded concrete impregnated with ferrous oxide. This core serves as a catalytic or contact substance during the operation of the system and 60 facilitates or promotes the desired conversion or actions in the oil body passing in vapor form through the converter. The core is supported within the tube by wire legs 9.

As shown in Figure 2, the core 8 in the 65 upper row B of converting tubes is of tapered

form. That is to say, the end of each core 8 at the inlet end of the converter is of greater diameter than the end of the core at the outlet or discharge end of the tube B. In the remaining tubes of the converter the cores may 70 be of uniform diameter, but it is important in carrying out the invention that the cores in the upper row B of the converter shall be tapered as disclosed. As previously explained, by so forming the core in the first or 75 inlet pass of the converter the effective area for oil vapor travel is restricted, with the result that the velocity of flow of the oil vapor through the inlet portion of the converter is relatively accelerated as compared 80 with those velocities which obtain in the remaining portions of the converter. By increasing the velocities heat transference is promoted between the oil vapor and the heated walls of the converter tubes. This enables 85 the oil vapors to be readily brought to a critical temperature wherein the desired reactions take place, and wherein there is but a minimum deposition of carbon or coke on the walls of the converter tubes. The velocities at the 90 inlet end of the converter range between four to seven thousand feet per minute, while those in the lower rows of tubes of the converter range between two to four thousand feet per minute. The temperature of the oil vapor 95 entering the converter is usually approximately 650° Fah., and this temperature is rapidly brought to a temperature in excess of 1000° F. in the inlet row of tubes of the converter. This is due to the fact that accelerated 100 velocities of oil vapor flow exist in the inlet end of the converter tubes, and also due to the fact that such inlet ends are exposed to the radiant heat developed within the combustion chamber of the setting. The oil vapors discharged from the converter are rapidly 105 cooled and suitably fractionated in any standard way to condense out motor fuel fractions.

It will be understood that I do not limit 110 myself to the specific construction described for securing accelerated oil vapor flow in the initial portion of the converting tubes, but reserve the right to employ any desired arrangement or other equivalent methods of 115 operation for securing the ends desired.

What is claimed is:

1. In a process of refining oil, the improvement comprising passing a rapid flow of vapors of oil substantially free from hydrocarbon constituents in the liquid state in a stream of restricted cross-section in a series of successive passes through a heater and heating the oil vapors during their passage therethrough to a temperature in excess of 1000° 120 F., and in regulating the flow of the oil vapors through the initial passes of said heater to obtain vapor velocities in said initial passes materially in excess of those existing in the 125 succeeding passes.

2. In a process of refining oil, the improvement comprising passing a rapid flow of vapors of oil substantially free from hydrocarbon constituents in the liquid state in an annular stream of restricted cross-section in a series of successive tube passes through a heater and heating the oil vapors during their passage therethrough to a temperature in excess of 1000° F., and in so controlling the passage of the vapors through said passes as to secure vapor velocities in the initial passes of the heater materially in excess of the vapor velocities which obtain in the succeeding passes of the heater, whereby the rate of heat transfer in said initial passes of the heater exceeds the rate of heat transfer in the following passes of the heater.

3. The method of producing low boiling point hydrocarbons from hydrocarbons of relatively higher boiling points, which consists in passing a current of hydrocarbon vapors through an elongated conversion zone of restricted cross-section, in so regulating the flow of the vapors through said zone as to obtain vapor velocities at the entrance portion of said zone of between four to seven thousand feet per minute, in subsequently reducing these velocities prior to the discharge thereof from said zone to a velocity rate of between two to four thousand feet per minute, and applying heat to the vapors passing through said zone to secure vapor temperatures in excess of 1000° F.

4. The method of producing low boiling point hydrocarbons from hydrocarbons of relatively higher boiling points, which consists in passing an annular current of oil vapor through an elongated conversion zone of restricted cross-section, in regulating the effective internal areas of said zone so that the velocity of vapor flow through the entrance portion of said zone will range between four to seven thousand feet per minute and in the following portions of said zone at a velocity range of between two to four thousand feet per minute, and in heating the oil vapors during passage through said zone to conversion temperatures in excess of 1000° F.

5. In an oil converter, an elongated tubular conduit having a substantially uniform internal diameter throughout the length thereof, and a core of varying cross-sectional diameter arranged to occupy an axial position within and extending longitudinally of said conduit, the larger end of said core being disposed in the oil inlet end of said conduit.

6. In an oil converter, an elongated conduit of restricted cross-sectional area arranged within the converter through which oil vapor is passed for heating purposes, said conduit possessing a substantially uniform internal diameter throughout the length thereof, and a core containing iron oxide positioned longitudinally and axially within

said conduit to provide for oil vapor flow through said conduit in annular form, said core possessing a greater diameter at one end than at its other and being arranged within said conduit so that the end thereof of greatest diameter is disposed in the vapor inlet end of said conduit.

In testimony whereof, I affix my signature,
CARY R. WAGNER.
